UNITED STATES PATENT OFFICE.

MORTON HAVENS, JR., OF ALBANY, NEW YORK.

BRANCH BOX.

1,014,704.

Specification of Letters Patent.

Patented Jan. 16, 1912.

Application filed March 24, 1906. Serial No. 307,785.

To all whom it may concern:

Be it known that I, MORTON HAVENS, Jr., of Albany, in the county of Albany and State of New York, have invented a certain 5 new and useful Branch Box, of which the following is a specification:

My invention has for its object the production of a branch box for electric wires, which is particularly simple and economical 10 in construction, and highly efficient and durable in use; and to this end it consists in the novel combinations and means hereinafter set forth and claimed.

In describing this invention, reference is 15 had to the accompanying drawing in which like characters designate corresponding parts in all the views.

Figure 1 is an elevation of a preferable construction of my branch box, a conduit 20 and a pair of wires being shown in operative relation thereto. Fig. 2 is a plan of the body of the branch box. Figs. 3 and 4 are sectional views taken, respectively, on lines A—A and B—B, Fig. 1. Fig. 5 is a 25 sectional view taken on line C—C, Fig. 2. Fig. 6 is an inverted plan of the closure.

The body 1 of my branch box is preferably hollow and elongated, and is formed of metal and provided with an opening 2 in 30 one side thereof, and with an inlet passage 3 communicating with the interior of the body. Opposing lengthwise portions of the inner face of the body are provided with diagonally arranged lugs 4 formed with 35 threaded sockets 5 extending through the outer and inner faces 6, 7 thereof. These faces 6, 7 are disposed between, and spaced apart from, the planes of the open side of the body 1 and the wall 8 opposite said open 40 side.

As best seen in Fig. 1, an end of a conduit 9 for the wires 10 extends within the passage 3, contiguous surfaces of the wall of the passage and the conduit being threaded 45 for facilitating securement and detachment of said branch box. Although in the illustrated construction of my branch box the passage 3 is shown as extending laterally from the body 1, it is obvious that the branch 50 box may be provided with one or more pas-

sages extending either downwardly or longitudinally.

The open side of the body 1 is provided with an elongated closure usually formed of a single piece of insulation, as porcelain, and 55 provided with one or more perforations 12, for permitting the outlet of one or more of the wires 10, the illustrated construction of the closure having perforations 12 in its ends for the outlet of both wires 10. Said 60 closure 11 is also provided with an elongated reduced portion 13 inserted into the opening 2, and having its inner face opposed to, and engaged with, the outer faces 6 of the lugs 4. A ledge 14 is provided on the closure 65 11 at the base of the reduced portion 13 and is opposed to, and spaced apart from, the edge 15. Any suitable connecting means, as screws 16, are passed through openings 17 in the closure 11 and into the threaded 70 sockets 5 of the lugs 4 for detachably securing said closure to the body 1.

By constructing the body 1 and the closure 11 as described, liability of breakage of the more or less fragile closure is reduced to a 75 minimum, since said closure engages the body only at separated points and in close proximity to the securing screws 16, and is formed of full thickness at said points of engagement. Moreover, the threaded sockets 80 5 are readily and cheaply formed with a minimum liability of injury to the tools used in the formation of said sockets.

What I claim is:—

A branch box for wires comprising a hollow elongated body formed with a passage 85 for the inlet of the wires, and with an open side, and having its inner face provided with a lug, the outer face of the lug being disposed between, and spaced apart from, the planes 90 of the open side and the wall opposite said open side, an elongated closure for the open side of the body, said closure being formed of insulating material and having a perforation for the outlet of a wire or wires, 95 and being provided with a reduced portion inserted into the opening of said open side, the inner face of the reduced portion being opposed to, and engaged with, the outer face 100 of the lug, and the closure being also pro-

vided with a ledge arranged at the base of the reduced portion and opposed to the edge surrounding said opening, and means connecting the closure and the lug for detachably securing the closure to the body, substantially as and for the purpose specified.

In testimony whereof, I have hereunto

signed my name in the presence of two attesting witnesses, at Syracuse, in the county of Onondaga, in the State of New York, this 20th day of March, 1906.

MORTON HAVENS, JR.
